UNITED STATES PATENT OFFICE

95,724

DESIGN FOR A BEER COIL CLEANER

Harry W. Anderson, Chicago, Ill.

Application March 19, 1935, Serial No. 55,943

Term of patent 3½ years

To all whom it may concern:

Be it known that I, Harry W. Anderson, a citizen of the United States, residing at Chicago, in the county of Cook and State of Illinois, have invented a new, original, and ornamental Design for a Beer Coil Cleaner, of which the following is a specification, reference being had to the accompanying drawing, forming part thereof, in which—

Figure 1 is a plan view of the article showing my design;

Fig. 2 is a front elevational view; and

Figs. 3 and 4 are opposite end elevational views.

I claim:

The ornamental design for a beer coil cleaner, as shown.

HARRY W. ANDERSON.
